UNITED STATES PATENT OFFICE

JOHN HOLTZMAN, OF NEW YORK, N. Y., ASSIGNOR OF ONE-HALF TO MAX D. ORDMANN, OF BROOKLYN, NEW YORK

FOUNTAIN PEN

Original application filed June 26, 1924, Serial No. 722,493. Divided and this application filed December 11, 1929. Serial No. 413,347.

This application is a division of my original application Serial No. 722,493, filed June 26th, 1924, for fountain pens and refillable pencils.

5 The present invention relates to fountain pens and the like, and contemplates the provision of simple and efficient means adapted to be operated by a simple turning movement for allowing the quick and easy filling of the pen.

10 The various objects of my invention will be clear from the description which follows, and from the drawing, in which,

15 Fig. 1 is a sectional view of a combination writing device including a fountain pen and pencil, the ink sack for the pen being shown compressed.

20 Fig. 2 is a longitudinal section thereof, showing the ink sack in its normal or extended position.

25 Fig. 3 is a cross-sectional view, taken on the line 3—3 of Fig. 2, showing by means of the shading, the shape of one of the cam surfaces, the overlying part being removed for that purpose.

Fig. 4 is a similar view, taken on the line 4—4 of Fig. 2, showing the annular walls in the cap for the reception of leads.

30 In that practical embodiment of my invention which I have illustrated by way of example, the writing device is shown as a combination fountain pen and refillable pencil. It will be understood, however, that the pencil portion may be eliminated or cut off or 35 finished similarly to fountain pens of the usual description, if desired, in a manner which will be obvious to those skilled in the art and hence, which need not be described or shown.

40 My improved pen includes an outer shell or barrel 10 which is preferably though not necessarily, formed integrally with a pen holding or terminal portion or head piece 11, adapted to removably receive the feeder 12 and the pen point 13.

Extending longitudinally through the barrel and attached to the feeder 12 as by means of a slip section 35, is a rubber ink sack 14 of the usual type. Said sack is adapted to be compressed to drive the air out therefrom

whereby a new supply of ink is sucked into the sack when it returns automatically to its normal shape. The compressing means for the sack includes a plate or leaf spring 15, one end of which is bent and fixed relatively to the barrel as at 16 being inserted into the recess 34 between the slip section 35 and the barrel 10. The other end of the spring 15 is attached as at 17 to a longitudinally displaceable member 18, whereby one end only of the plate spring 15 may be moved longitudinally to bow the spring and thereby to compress the sack 14. Said member 18 engages the end 17 of the plate spring 15 so that longitudinal movement of the member 18 causes similar movement of the end 17 and thereby bows the spring. Said member 18 is movably fitted in the end of the barrel opposite that of the head piece 11, and is arranged for 60 operation by a cooperating cam.

Toward this end, the inner face of the member 18 is formed or associated with cam surfaces 19 which engage corresponding cam surfaces 20 associated with the rotatable member 21. To maintain the member 21 against longitudinal movement in the barrel, an annular groove as 22 is formed therein, suitable pins as 23 projecting from the barrel, being inserted into said groove and thereby allowing rotation only of the member 21. Part of said member may project from the barrel and the projecting part may be serrated as at 24 to provide a roughened surface adapted to be conveniently gripped by the operator for the proper manipulation thereof. 75

If desired, the member 21 may be continued in the form of a tapered casing 25 for forming the pencil part of my device and for the reception of a suitable lead feeding or supporting mechanism and sleeve 26, though it will be understood that where my invention is to be applied only to fountain pens, the mechanism 26 may be omitted as well as the tapered portion 25 and the member 21 may 80 be terminated at or about the line 27.

By turning the member 21, the inner member 18 is moved inwardly or outwardly as shown in Fig. 1, thereby compressing or flattening the spring 15, as the result of which 100

the sack will be actuated to draw in or discharge ink as the case may be.

The cap of the pen may comprise two sections, an elongated tubular section 28 and a shallow disc-like capping section 29. An annular chamber as 30 may be formed interiorly of the cap 28 for the reception of leads 31 or other material while the section 29 is adapted to be removably screwed on to the 10 threaded outer end of the section 28 to removably close said chamber 30.

It will be seen that a substantially straight spring 15 may be employed as illustrated except that one end is bent as at 16, and 15 that a cam member is provided at the other end. Because of this straight construction, the spring will maintain its shape without permanent buckling or bending.

It will be understood that while I have 20 shown and described a specific embodiment of my invention, I do not intend to limit myself thereto but intend to claim my invention as broadly as may be permitted by the state of the prior art and the scope of the 25 appended claims.

I claim:

1. A fountain pen having in combination, 30 a hollow barrel, an ink sack in the barrel, a spring in said barrel at one side of the sack for compressing the sack, a cam, a straight end on the spring inserted into the cam, a bent end on the spring fixed relatively to the barrel in the recess provided between the sack and the barrel, a rotary member mounted at 35 one end of said barrel, a second cam carried by said member and being in operative engagement with the first cam, and in direct engagement with the inner wall of the barrel, said member adapted to be manually rotated 40 and arranged to compress or release said sack at a single turn of not more than 360° relatively to the barrel.

2. A fountain pen including a collapsible 45 ink sack open at one end, a hollow slip section inserted in said end, a feeder removably inserted in the slip section, a spring adapted to effect collapse of said bag in the ink charging direction fixed at one end to the barrel near the slip section, an end plunger adapted 50 to bend said spring, a revolute external member, means projecting from the barrel to prevent longitudinal movement of the member, and a cam surface associated with said member whereby the rotation of said 55 member operates the sack to effect the filling of said sack with ink.

3. A fountain pen having, in combination, 60 a tube constituting a barrel, a section in an end of the tube, the interior of the barrel providing a recess near the section, an ink bag in the barrel, a spring in the barrel for compressing the ink bag, an end of the spring being bent into the recess, the recess having 65 walls on both sides of the bent end of the spring to confine the said bent end of the

spring in the recess, and means for actuating the spring to compress the bag including a one-piece member entering the barrel and having an outer accessible portion, and means projecting from the barrel to prevent longitudinal movement of the member while permitting rotation thereof.

4. A fountain pen having, in combination, 70 a barrel having an interior side face and an end face and having a recess at the side face near the end face, an ink bag in the barrel, a spring in the barrel for compressing the ink bag and having a bent portion extending into the recess, the recess having walls on both sides of the bent end of the spring to confine the said bent end of the spring in the recess, and means near the other end of the barrel for actuating the spring, comprising 75 a pair of cooperating cams each of a single piece of material, one of said cams projecting outside of the barrel for access by the user, and means on the barrel for preventing longitudinal movement of one of the cams relatively to the barrel.

5. A fountain pen having, in combination, 80 a tube constituting a barrel having an interior side face and two ends, a slip section in one end of the tube, the barrel providing a recess disposed opposite to a portion of the section, an ink bag in the barrel, a spring in the barrel for compressing the bag, one end of the spring extending in between the side face and the section and into the recess, the other end of the spring extending toward the other end of the barrel, and means engaging the said other end of the spring for actuating the spring to compress the bag comprising 85 a pair of cooperating cams, one of said cams being adapted to support a pencil mechanism, and means for preventing longitudinal movement of the last-mentioned cam.

6. A leaf spring, one end of which is bent and the other end of which is provided with a cam fixed thereto, and means for moving the cam longitudinally to bow the spring, 90 said means being rotatable and fixed against longitudinal movement.

7. A fountain pen having, in combination, 95 a barrel having an interior side face and an end face and having a recess adjacent the side face, an ink bag in the barrel, a spring in the barrel for compressing the ink bag and having a bent portion extending into the recess, the spring having a longitudinally movable cam, a closure mounted on the barrel near the end face and rotatable with respect to the barrel, a cam rotatable with the closure to move the first-named cam longitudinally to effect actuation of the spring, 100 and means on the barrel and entering the second-named cam for guiding the second-named cam in its movement.

8. A fountain pen having, in combination, 105 a hollow barrel, a spring, the body of which is substantially straight, one end of the spring 110

being bent and the other end being provided with a cam, a second cam cooperating with the first-named cam to move the same longitudinally, and having an annular groove 5 therein, and means projecting from the barrel into the groove to guide the second cam.

9. A fountain pen having, in combination, a hollow barrel having a recess provided with a stop in the inner wall near one end; an ink 10 bag in the barrel; a bag compressing leaf spring in the barrel at the side of the ink bag having one end bent outwardly and lying in said recess with its end held by said stop; and means for moving the other end of the 15 spring to bow the same to compress the ink bag including cooperating guide means on the barrel and the leaf spring at one end of said spring, and a cam on the end of the leaf spring adjacent said guide means.

10. A fountain pen having, in combination; a hollow barrel having a spring-receiving recess provided with a stop near one end; an ink bag in the barrel; a bag compressing leaf spring in the barrel at the side of the 20 ink bag having one end bent outwardly and lying in said recess with its end held by said stop; and means for moving the other end of the spring to bow the same to compress the ink bag including cooperating guide means 25 on the barrel and the leaf spring at one end of said spring, and a cam on the end of the leaf spring adjacent said guide means.

11. A fountain pen having, in combination, a barrel, an ink bag in the barrel, a leaf 30 spring in the barrel at one side of the ink bag for compressing the ink bag, co-operating guide means on the barrel and the leaf spring at one end of said spring, and a cam on the end of the leaf spring adjacent said 35 guide means.

12. A fountain pen having in combination, a barrel, an ink sack in said barrel, a spring with one end offset outwardly of the remainder thereof, a rivet fixing said end 40 relatively to said barrel between the sack and the barrel, said spring being arranged for compressing said sack, a cam fixed to the other end of the spring and having its outer surface in direct engagement with the barrel, 45 a rotary member mounted on the barrel at one end thereof, and forming the support for a pencil feeding mechanism, a cam rotatable with said member to move the first named cam longitudinally to effect actuation of the 50 spring, said rotatable cam being provided with an annular groove, and a pin projecting inwardly from the barrel into said groove and adapted to cooperate with the walls of the groove to prevent longitudinal movement 55 of the rotatable cam.

13. A fountain pen having in combination, a hollow barrel, an ink sack in the barrel, a hollow slip section in and arranged 60 concentrically of the barrel and of less outer 65 diameter than that of the barrel and having

a smooth outer portion inserted into the sack, a sack compressing spring in said barrel and disposed at one side of the ink sack, one end of the spring being fixed relatively to said barrel between that end of the sack held by the slip section and the barrel, and the other end being provided with a cam in direct engagement with the barrel, and a one-piece rotary member mounted at one end of said barrel cooperating with said cam for moving 70 said other end of the spring to bow the same for compressing said sack and having a shoulder thereon engaging the end of the barrel.

14. A fountain pen having, in combination, a barrel, an ink sack open at one end in the barrel, a leaf spring for compressing the sack, one end of the spring being fixed relatively to said barrel near the open end of the sack and the other end being provided with a cam, and a one-piece rotatable member 75 mounted at and having a shoulder engaging one end of the barrel and having means thereon for actuating said cam for bending said spring to prevent relative longitudinal movement of the member, said member when partially rotated, relatively to said barrel, causing said cam actuating means to flex the spring and thereby compressing the sack, and releasing said sack upon another partial rotation of said member for filling said sack 80 with ink.
